(57) **CLAIM**

The ornamental design for a combined stun gun and flashlight, as shown and described.

DESCRIPTION

FIG. 1 is a front perspective view of a combined stun gun and flashlight, showing a first embodiment of my new design;

FIG. 2 is a front elevational view of FIG. 1;

FIG. 3 is a rear elevational view of FIG. 1;

FIG. 4 is a top plan view of FIG. 1;

FIG. 5 is a bottom plan view of FIG. 1;

FIG. 6 is a left-side elevational view of FIG. 1;

FIG. 7 is a right-side elevational view of FIG. 1;

FIG. 8 is a rear perspective view of FIG. 1;

FIG. 9 is a front perspective view of a second embodiment thereof;

FIG. 10 is a front elevational view of FIG. 9;

FIG. 11 is a rear elevational view of FIG. 9;

FIG. 12 is a top plan view of FIG. 9;

FIG. 13 is a bottom plan view of FIG. 9;

FIG. 14 is a left-side elevational view of FIG. 9;

FIG. 15 is a right-side elevational view of FIG. 9; and,

FIG. 16 is a rear perspective view of FIG. 9.

The broken lines depict portion of the combined stun gun and flashlight that form no part of the claimed design.
